UNITED STATES PATENT OFFICE

WILLIAM H. LUTZ, OF SAN FRANCISCO, CALIFORNIA

NECKTIE SUPPORT

Application filed January 28, 1932. Serial No. 589,476.

This invention relates to improvements in necktie supports and has particular reference to a means for supporting a necktie upon a collar button.

5 A further object is to produce a device which is economical to manufacture.

A still further object is to produce a device which is neat in appearance and therefore one which will not detract from the appearance of a necktie.

10 Other objects and advantages will be apparent during the course of the following description.

In the accompanying drawing forming a part of this specification and in which like numerals are employed to designate like parts throughout the same,

15 Fig. 1 is a front elevation of my device showing a portion of a shirt and necktie in broken lines.

Fig. 2 is a perspective view of one portion of my device as the same would appear when attached to a bow tie,

20 Fig. 3 is a perspective view of the socket portion of my device,

Fig. 4 is an enlarged detail cross sectional view,

Fig. 5 is a cross sectional view taken on the line 5—5 of Fig. 1, and

25 Fig. 6 is a cross sectional view taken on the line 6—6 of Fig. 4.

Many persons find it very difficult to tie a tie so that it will look neat. I have provided means whereby a plate may be attached to the rear of the tie after it is first tied, which plate carries a stud adapted to be received in a socket portion, which socket portion is formed upon a button to be placed through the usual button holes of the collar band.

30 In the accompanying drawing, wherein for the purpose of illustration is shown a preferred embodiment of my invention, the numeral 5 designates a plate which is adapted to be sewed to a necktie 6. A stud 7 is secured to the plate 5 in any convenient manner and carries a head 8 which is adapted to enter a resilient socket 9, which socket is preferably formed of rubber or resilient material

and is held in a cup-shaped portion 11 of the button 12.

The result of this construction is that when the plate is attached to the tie and the collar button has been placed through the button holes in the neck-band, the head 8 may be forced into the resilient socket 9 of the collar band after which the tie will be retained in place until the wearer forcibly pulls the head 8 out of its socket.

55 It will thus be seen that this device will accomplish all the objects above set forth.

It is to be understood that the form of my invention herewith shown and described is to be taken as a preferred example of the same and that various changes relative to the material, shape, size and arrangement of parts may be resorted to without departing from the spirit of the invention or the scope 60 of the subjoined claim.

65 Having thus described my invention, I claim:—

In a device of the character described, a plate for attachment to a necktie, a shank secured to said plate, a head formed on said shank, a collar button cooperating with said shank, said collar button having a cupped shaped portion, a resilient lining formed in said cup whereby the head of said shank may be inserted in said cup and engaged by said lining.

70 In testimony whereof I affix my signature.

WILLIAM H. LUTZ.
